APPARATUS FOR INTERNAL GRINDING

Richard A. Heald, Worcester, Mass., assignor to
 The Heald Machine Company, Worcester,
 Mass., a corporation of Massachusetts

Application April 13, 1942, Serial No. 438,754

6 Claims. (Cl. 51—48)

The present invention relates to internal grinding by the centerless or chuckless method. More particularly, the invention resides in certain novel procedures and arrangements which enable the centerless method or technique to be utilized in a highly advantageous fashion for the precision internal grinding of various types of workpieces which, because of irregularity of shape, susceptibility to distortion, unwieldiness, or any other reason, can only with considerable difficulty and much loss of time be handled in a chuck-equipped or center-type internal grinder.

An example of such work is furnished by certain relatively-large thin-walled cylinders having a multiplicity of external heat-radiating fins, such as are used in airplane engines. In finishing the bores of such cylinders (or similar workpieces) on a center-type internal grinding machine, it has never been possible to avoid frequent and lengthy periods during which said machine must remain wholly idle and unproductive; these interruptions are imposed by the necessity, following each introduction of an unground cylinder to the workholder of the machine, for laborious and time-consuming manipulations of said cylinder within said workholder, to make certain, before any grinding is undertaken, that the thin-walled bore runs absolutely true, in the rotation of the work holder. This truing-up of the work, always a slow and painstaking task, is rendered even more so because the operator, being obliged to stand at some distance from the workholder, is in an awkward and disadvantageous position for the performance of the many work-positioning and clamping operations that are required.

My invention overcomes all these difficulties and delays by an arrangement and procedure which enables each cylinder's (or other workpiece's) truing-up operation to be performed in a position convenient to the operator and to be completed during my improved machine's grinding period on a preceding cylinder or other workpiece; notwithstanding this said truing-up is in every case secured with reference to the selfsame rotational axis that is effective for the workpiece's rotation during the ensuing grinding operation on the workpiece bore. By this utilization of the grinding time on one workpiece for the truing-up of the next workpiece, my invention obtains a materially greater rate of production than was heretofore obtainable in the internal grinding of work of this class.

My invention also provides novel means by which loading and handling of such cylinders

or similar unwieldy pieces of work is greatly facilitated. Other and further objects and advantages of my invention will more fully appear from the following detailed description, taken in connection with the accompanying illustrative drawings in which

Fig. 1 is an isometric view showing the principal elements of an internal grinding machine embodying the principles of my invention.

Fig. 2 is a view showing portions of the machine at the left hand end of Fig. 1, in side elevation, other parts being shown in section.

Fig. 3 is a large scale sectional view of parts shown at the right hand end of Fig. 2.

Fig. 4 is a sectional view of one of the work-receiving shuttles or thimbles, and showing a piece of work therein.

Figs. 4a and 4b are fragmentary sectional views, on lines 4a—4a and 4b—4b respectively of Fig. 4, showing certain details of said work-receiving shuttle.

Fig. 5 is a diagrammatic showing of certain electrical and hydraulic features and connections of said machine.

Like reference characters refer to like parts in the different figures.

Fig. 4 shows one of the airplane engine cylinders mentioned above as typical of the kinds of workpieces which despite their difficult or unwieldy nature, can be expeditiously handled for precision bore grinding by the apparatus of my invention. The external surface of said cylinder, as shown, has great numbers of thin heat radiating fins *a*, *a* projecting outwardly both from its barrel portion *b* and from its head portion *c*. Because of these fins, and also because a cylinder wall of such thinness is very susceptible to distortion, it is not practical to hold such a workpiece for internal grinding by means of the usual rotary chuck having radial work-gripping jaws. Hence the previous practice in the bore grinding of such cylinders or like workpieces, has been to equip the internal grinding machine with a rotary pot-type chuck large enough to receive the entire cylinder, and fitted with special devices for holding the cylinder by engagement preferably with non-distortable portions thereof, such as its annular barrel flange *d* and/or any unfinned portions *e* of the cylinder head.

To properly chuck such a workpiece under these conditions is always a long and tedious operation. With such a thin-walled cylinder (see Fig. 4) only a very limited removal of stock by bore grinding is permitted, and this stock removal in the nature of things must be distributed

absolutely uniformly. Hence it is incumbent on the operator before any bore grinding is attempted, to make certain that the bore surface runs true in the rotation of the chuck or work holder of the machine. This truing-up of a piece within the chuck always involves repeated startings and stoppings of the chuck's rotation, repeated testings of the bore throughout its length with the feeler of a suitably mounted dial indicator or equivalent device, and repeated clampings and unclampings of the workpiece for the needed positional readjustments within the chuck, before the required exactly trued-up position, by such cut-and-try methods, can be achieved. During all these prolonged periods of manipulation on each workpiece, the internal grinding machine that provides this special chuck must remain idle and wholly unproductive.

These long and frequent periods of enforced idleness for a machine used to grind a succession of such bores, are practically eliminated, according to my invention, by employing an internal grinding machine of the centerless or chuckless type having special equipment as hereinafter described which enables this truing-up of each workpiece bore in preparation for grinding to be completed during the bore-grinding period of said machine on the preceding workpiece; thus said machine is rendered almost continuously productive.

Referring first to Figs. 1 and 2, the internal grinding machine of my invention has a suitable base that comprises an elongated portion 1, which supports the work-rotating and grinding instrumentalities, and also a shorter portion 1a, substantially at right angles to the portion 1, for a purpose to be hereinafter described. The base portion 1 has the usual ways 2, 2 (Fig. 2) for the travel of a reciprocating table 3, the latter providing transverse ways 4, 4 for the movement of a cross slide 5 which carries the wheelhead 6 of the machine. Suitably journaled in said wheelhead is the spindle 7 of rotating grinding wheel 8, the latter as here shown being driven by a belt 9, connecting a pulley 10 on said spindle with a driving motor 11 suitably mounted on cross slide 5.

The base portion 1 supports a transverse bridge 12 which spans the longitudinal ways 2, 2 substantially in line with the shorter base portion 1a. On this bridge 12 are mounted the machine's centerless or chuckless work-supporting and work-rotating instrumentalities, consisting as shown of a backing or regulating roll 13, a support roll 14, and a pressure roll 15. The backing roll 13 is supported for rotation by suitable bearings carried by bridge 12 at the opposite ends of said roll, the latter being driven in any suitable manner, as by a belt connection 16, Fig. 2, to a shaft 17 journaled at the rear of base 1, said shaft in turn being driven by a belt connection 18 to a driving motor 19. The effective contact surfaces of said backing roll 13 are the spaced-apart accurately-finished cylindrical surfaces 20, 20 of limited width at the two ends of said roll, immediately adjacent the latter's bearings. Between said surfaces 20, 20, said backing roll 13 is appreciably reduced in diameter, as shown at 21, for a purpose to be later described.

For "centerless" reception between the rolls 13, 14, 15, the machine's equipment includes at least two hollow work-receiving shuttles or thimbles, as indicated at 22 and 22a, Fig. 2, each shuttle presenting accurately-finished externally-cylindrical surfaces having the same spacing as the

75 backing roll surfaces 20, 20. Each shuttle, for the particular type of workpiece here selected for illustration may be substantially of the construction shown by Figs. 4, 4a and 4b. The shuttle there shown includes a shell or body 23 having at one end an inturned flange 24, the latter presenting an external circular surface 25 to which is fitted a hardened end ring 26. At its other end the shell or body 23 has an inturned flange 27, to whose circular surface 28 is fitted a hardened end ring 29, the two rings 26 and 29 being secured to the shell 23 by any suitable means, such as the bolts 23'. The outer peripheries of the two end rings 26 and 29 are accurately finished to provide the aforesaid spaced cylindrical surfaces 30, 30 adapted to have rolling contact with said backing roll surfaces 20, 20 and with the support and pressure rolls 14 and 15. Said end rings 26 and 29 beyond their surfaces 30, 30 have flanges 31, 31 adapted, when the shuttle or thimble is operatively positioned in the machine, to overlap the ends of said rolls 13, 14, 15; these flanges have accurately finished peripheral surfaces 31a, 31a, for a purpose to be later described.

25 Interiorly of the shell 23 of each shuttle are provided suitable devices which enable a cylinder or other similar workpiece to be clamped and held by endwise, rather than radial, pressure, thus avoiding any distortion. To this end as shown by Fig. 4, the flange 24 of the shuttle carries a series of equally-spaced hardened buttons 32, 32, usually three in number, against which is seated flange *d* of cylinder barrel *b*, when the latter as shown in Fig. 4 is entered in the shuttle from the latter's other or left hand end. Suitable clamping members, usually three in number, adapted to bear against the opposite side of flange *d* are indicated at 33, 33, each of these members being turnable on a suitable post 34 extending lengthwise of the shell 23, and being accessible through a window or opening 35 of said shell, for turning out of the way of said flange, (Fig. 4a), and then for turning into clamping position, (Fig. 4) after said flange is seated against the buttons 32, 32. 30 Preferably, each clamping member 33, is adapted to be held frictionally in any position to which it is turned by the drag imposed by a suitable coil spring 36 surrounding the post 34.

35 Each clamping member 33, when in operative position preferably bears at its ends only (by lugs 40, 40) against flange *d* and a suitable surface of the shuttle (a wall of window 35). Adequate clamping pressure, between said bearing points, is applied by the screwing down of a sleeve 37, in threaded engagement with post 34, and having a head of hexagonal or square section, as indicated at 38, which is accessible through a window or opening 39 of the shell 23 for the application of a wrench or other suitable tool by which to turn said sleeve for the tightening or loosening of its associated clamping member 33.

40 Additional devices for supporting the inserted workpiece are preferably provided at the other end of the shuttle, these being a series of fingers 41, 41, usually three in number (only one appearing in Fig. 4), for peripheral engagement with the flange *e*. Each of said fingers projects from a bolt 42, rockably mounted in the end ring 29 and adjacent flange 21, for turning movements that permit said fingers, before insertion of the workpiece, to be swung out of the way of the barrel flange *d*; afterwards, said fingers 41, 41 are turned, so as to bear against the periphery of flange *e*, to support and steady the workpiece

at this end of the shuttle, being locked in such operative positions by means of suitable nuts 43, 43 on each of the carrying bolts 42, 42. Said nuts are accessible for the application thereto of wrenches or the like through other openings or windows 44, 44 of the shell 23.

Such a shuttle 22 or 22a carrying a cylinder or other workpiece to be internally ground, provides the means by which said workpiece is subjected to rotation during the grinding operation on its bore, this rotation, upon introduction of such loaded shuttle to the machine's rolls 13, 14 and 15 being on an axis determined by the shuttle's pre-formed external surfaces 30, 30 that are contacted by said rolls. According to my invention these selfsame pre-formed surfaces 30, 30 which govern a workpiece's rotation during grinding, are utilized prior to such grinding, to govern the rotation by which the truing-up of said workpiece's thin-walled bore within a shuttle is secured. To this end, my machine, on its base portion 1a, provides means of the same character as the aforesaid "centerless" rolls 13, 14, 15, for shuttle support and rotation by rolling contact with the shuttle surfaces 30, 30, in association with suitable truing-up devices arranged for contact with the bore of the workpiece contained in each so-rotated shuttle.

As shown in Figs. 1 and 2, base portion 1a carries a suitably journaled roller 45, in line with and of substantially the same length as the rolls 13, 14, 15. The upper portion of this roller 45 projects appreciably above the level of a pair of spaced guides 60, 60 hereinafter described, which are secured to the top surface of base portion 1a. The roller 45 is adapted to be driven in any suitable manner, as by belt connection 46 with a shaft 47 which is driven through suitable reduction gearing, not shown, by a driving motor 48, the latter being controlled for starting and stopping by a conveniently located push button switch 49, shown in Fig. 2, at the end of base portion 1a.

For cooperation with roller 45 the machine provides a similar roller 50 nearer to the "centerless" rolls 13, 14, 15, and here shown as journaled in a yoke 51, whose other end is pivotally mounted at 52 within the base portion 1a. A projection or lug 52a on the under side of said yoke is substantially in line with a member 53 which is vertically slidable in the base. At its lower end the member 53 carries a cam roller or follower 54, the latter resting upon a cam surface 55 provided by a member 56 which is secured to a rock-shaft 57, suitably journaled in a projecting boss 58 provided by the front wall of base 1a. To the outer end of the rockshaft 57 is secured an operating lever 59, for raising or lowering the roller 50, by rocking of its supporting yoke 51 about the pivot 52; that is, when the lever 59 is swung clockwise by the operator to carry the higher part of cam surface 55 beneath the member 53, the roller 50 will be raised substantially to the level of the roller 45, the extent of this movement being determined by engagement of a lug 61 on yoke 51 with a stop screw 62 on the base. Rocking of lever 59 in the opposite direction carries the lower part of cam 55 beneath member 53, to drop said roller 50 below said pair of guides 60, 60, this lowering movement being limited by engagement of a pin 63 projecting from the base by the end of a slot 64 in member 53, in which said pin is received.

The two guides 60, 60 constitute part of a track on which the work-carrying shuttles are adapt-

ed to be rolled, in one direction toward the grinding station provided by the rolls 13, 14, 15 and in the other direction toward the truing-up station provided by the rollers 45 and 50. For this purpose said guides are preferably of the angular cross-section shown at 65, Fig. 1; their spacing apart, in opposed relation, is such as to receive upon their inner flat surfaces 66 the peripheral surfaces 31a, 31a of the shuttle flanges 31, 31, the latter being inside of and confined by the upright guide surfaces 67. A newly-loaded shuttle on said track is permitted, by depression of roller 50, to be rolled to the left, Figs. 1 and 2, into engagement with the roller 45; thereupon, by the clockwise rocking of lever 59 the roller 50 will be raised into operative position, with a resultant slight lift of the shuttle, to transfer its support from the flat track surfaces 66, 66 to the accurately finished peripheral surfaces 68, 68 at the ends of these two rollers, which surfaces 68, 68 have the same spacing as the shuttle surfaces 30, 30. Thus, upon starting up of the driving motor 48 for the roller 45 the shuttle will be rotated on an axis determined by its pre-formed externally-cylindric surfaces 30, 30, for the truing-up, by aid of associated devices now to be described, of the bore of the workpiece carried by said shuttle.

In association with the rollers 45 and 50 is provided a sensitive indicating mechanism of any type well known in the art, to aid in the truing-up of the bore of a workpiece contained in a shuttle which has been moved as above described onto said rollers, for rotation thereby. Said indicating mechanism as here shown is carried by a bracket 69 secured to and extending upwardly from the base portion 1a, and said mechanism may consist of an arm 70 pivoted at 71 to said bracket, and carrying adjustably at its free end an elongated member 72 which extends at right angles to said arm. Said elongated member 72 is thus adapted by adjustment of its position on the arm 70, to be projected to a greater or less extent into the bore of a workpiece whose position within a shuttle on said rollers 45 and 50 is being trued-up. At its inner end, for contact with said bore, said member 72 carries the usual delicately-mounted feeler 73, whose varying displacements resulting from such contact are communicated, by suitable movement-multiplying connections ordinarily employed in mechanisms of this character, to the pointer of a dial indicator 74 carried by the outer end of member 72.

The use of such or similar indicating devices, in truing-up by cut-and-try methods the position of rotating workpieces to the axis of such rotation is well known in the art, and needs no extended description. However, it should be particularly noted that such truing-up operations in the machine of my invention are performed under conditions which are most conducive to accuracy of result and to the facility with which the operator may achieve such accuracy. Heretofore, in a chuck-equipped or center-type machine, such truing-up has had to be performed under very difficult conditions; the operator in such case being obliged to work from an awkward position, because of the relative inaccessibility of the indicating mechanism and the workpiece surfaces contacted thereby. These handicaps are entirely overcome in my machine, which permits the operator to stand directly in front of the work during the truing-up operation, and to have free and full access thereto from the back and from all sides.

My invention further provides mechanism which greatly facilitates the loading and handling of these work-carrying shuttles 22 and 22a. To this end, the machine provides between its grinding station and its truing-up station, as above described, a shuttle-loading station, the base portion 1a for this purpose being reduced in height to provide a supporting surface 75 at a relatively low level. On this portion of the base is mounted a turntable 76, the same consisting essentially as shown in Figs. 1 and 2 of a horizontal circular plate 77 mounted on the end of a vertical shaft, not shown, the latter being suitably journaled in bearings provided in a shell or casing 80 which is supported on and secured to the base surface 75 by a flange 81.

Above and to the rear of turntable 76, the base portion 1a supports a rockshaft 82, the latter extending horizontally lengthwise of said base portion, and being mounted in suitable bearings not shown. Secured to said rockshaft 82 is a shuttle-elevating member 84 which provides two portions at right angles to each other, namely a portion 85 that is adapted to be engaged by the shuttle peripherally and a portion 86 adapted to be engaged by the end of the shuttle. In the particular angular position of rockshaft 82 which is shown by Figs. 1 and 2, the portion 85 stands vertically and the portion 86 projecting laterally from the lower end of portion 85 stands horizontally; in such position, said portion 86 has its upper surface 87 substantially at or slightly below the level of turntable 76, the middle part of member 86 for this purpose being cut away at 88 to receive said turntable between the end portions 89, 89 that are adjacent to and substantially flush with the turntable surface.

In this shuttle-receiving position of member 84, a shuttle 22 or 22a resting by its end ring 26 on the turntable 76, overlaps the end parts 89, 89 of member 86, and has its flanges 31, 31 seated against two spaced track or guide members 60a, 60a corresponding in section, spacing and arrangement to the guide members 60, 60, and carried as shown in Figs. 1 and 2 by the vertical portion 85 of member 84. As shown in Figs. 1 and 2, the track surface 66 of each of these guides 60a, 60a has midway of its ends a shallow depression 90 which permits the adjacent shuttle flange 31 in each case to project slightly beyond or below the flat track surface 66.

A shuttle 22 or 22a thus resting on the turntable, is in convenient position for the lowering endwise into same of a cylinder or like workpiece, and the turntable supporting said shuttle provides a convenient means by which to swing the same into different angular positions, for access to the several clamping devices 33 and steadyng fingers 41 by which is obtained preliminarily the secure attachment of the workpiece to the shuttle, so that the two parts can thereafter be handled together. In such handling of a so-loaded shuttle, the first operation involves an upward counterclockwise swinging of member 84 through approximately 90 degrees to carry its portion 85 to a horizontal position; to this end, the rockshaft 82 is arranged to be rocked back and forth by power, through an angular distance of approximately 90° by any suitable means, said rockshaft for this purpose having a drive connection, through speed-reduction gearing of any suitable character, with the shaft of a reversible motor 97, also supported at the rear of base portion 1a. Said motor 97 is controlled by suitable push-button switches 98, 98 preferably mounted, as

shown in Figs. 1 and 2, adjacent the switch 49 for the driving motor of roller 45; associated with each switch 98, 98 is an automatic mechanism of any well known type, not shown, by which to always bring the motor 97 to a stop after it has run the required number of revolutions to move the rockshaft 82, by the above described connections through 90 degrees, in either direction. That is, upon depressing one of the switch buttons 98, the motor 97 will obtain an upward swinging of member 84 through 90 degrees, thereby transferring the loaded shuttle's support from arms 89, 89 to the track sections 60a, 60a, and at the completion of this movement the shuttle will be restrained from any accidental rolling in either direction, by the reception of its flanges 31, 31 in the shallow depressions 90, 90. The member 84 will be stopped and held in this upper position by the automatic stopping of motor 97. Afterwards, the so-raised member 84 can be used to lower a shuttle that has been rolled onto it, by depression of the other motor switch 98, for driving the motor 97 in the opposite direction, this motor actuation being stopped after shaft 82 has turned through 90 degrees, to dispose the member 84 in the position shown by Figs. 1 and 2, with the shuttle resting by its end ring 26 on the turntable 76 and arms 89, 89 of portion 86.

The elevation of member 84 as above described aligns the track sections 60a, 60a at one end with the two track sections 60, 60 that lead to the truing-up station, and at the other end with two similar track sections 60b, 60b which are carried by bridge 12 and which lead to the grinding station of the machine. These other track sections 60b, 60b are at the same level as sections 60, 60; this track level, as shown in Figs. 1 and 2 is slightly above the upper surface of the support roll 14, and the track sections 60b, 60b are extended to partly overhang said roll, so that a loaded shuttle as it rolls off the ends of said track sections will deposit itself in the "grinding throat" which is formed by the backing roll 13 and support roll 14.

The gap is the shuttle track which is bridged by the above described track sections 60a, 60a of member 84 is also adapted at other times to be bridged by other similar track sections 60c, 60c, the latter being carried by a generally flat member 99, whose central portion as shown in Fig. 1 has a lateral offset 100 by which to obtain pivotal mounting of said member on the shaft 82. Said member 99 remains for most of the time in its vertical inoperative position shown by Fig. 2; at certain intervals, it is seized by the operator and swung downwardly to horizontal position, being stopped at track level by the abutment of its track's overhanging cleats 101, 101 against the upper surfaces of track sections 60, 60.

In this horizontal position of member 99, its track sections 60c, 60c align with the track sections 60, 60 and 60b, 60b, to complete the track along which a shuttle, after final positioning and clamping of its contained workpiece at the truing-up station, is rolled into grinding position, it being understood, of course, that previously the way will have been cleared for such movement by the discharge from grinding position of the other shuttle, and the lowering of said other shuttle by member 84 onto table 76 for removal of the workpiece whose bore-grinding has been completed. A prerequisite to this discharge from grinding position of a work-containing shuttle is the elevation to inoperative posi-

tion of the pressure roll 15, which during each grinding operation bears downwardly on the shuttle then in the "grinding throat," and has rolling contact with the shuttle surfaces 30, 30.

According to my invention the movements of pressure roll 15 between operative and inoperative positions are utilized most advantageously for shuttle discharge (at completion of grinding) and shuttle deposit (at commencement of grinding), the pressure roll movements for this purpose being actuated hydraulically, preferably by the same fluid pressure medium which usually serves in grinding machines of this and other types, to produce the table movements by which are obtained the relative reciprocatory traverse between grinding wheel and work and the approach and separation of these parts, at the beginning and end respectively of each grinding operation. The table 3 of my machine is preferably connected to and actuated by such a system; the latter, however, forms no part of the present invention, and a description thereof is unnecessary. It is sufficient to note that in my machine a supply of fluid under pressure, whether it be from the actuating system of Table 3 or from any other source, is available for the operation of a piston and cylinder unit which, as will now be described, secures the deposit of each shuttle, without impact or shock, at the bottom of the grinding throat, and subsequently its discharge from said throat, this mechanical handling of each shuttle being accompanied by raising and lowering movements of pressure roll 15.

As shown in Fig. 3, there is carried by the bridge 12, above the bearings of backing roll 13, a suitable bracket 102, which at its opposite ends provides aligned trunnions 103, 103 for the pivotal support of a member 104, the latter being of inverted-box form, and providing near its outer end suitable bearings 105, wherein the pressure roll 15 is journaled, in position for rolling contact with shuttle surfaces 30, 30 when the member 104 is swung downwardly about its pivotal mounting 103. The swinging movements of member 104 are controlled by a hydraulically actuated piston 106, which is contained in a cylinder 107, secured as here shown to the back side of bracket 102. A rod 108 extending forwardly from piston 106 is suitably connected as shown in Fig. 3 with the pivoted member 104 to obtain, by the admission of pressure fluid to the left hand end of cylinder 107, the upward swinging of said member, and by the discharge of such pressure fluid from said cylinder the downward swinging of said member. To this end, as shown in Fig. 3, member 104 provides a pivotal mounting 109 for a block 110, the latter being offset from trunnion 103 so as to be in line substantially with the piston rod 108. Said rod 108 has at its free end an enlargement 111 wherein is formed a slot 112 which slidably receives the pivoted block 110, this slidable and pivoted connection between the piston rod 108 and the member 104 permitting the latter to respond by angular movement to the straight line movement of the former.

Secured to the underside of member 104 is an elongated downward-extending arm 113; the latter on account of the free space created by the reduced-diameter portion 21 of backing roll 13, is permitted to pass downwardly between said backing roll and a shuttle in the grinding throat, without contact or interference with either of said parts in the zone of their tangency; below said zone of tangency the arm 113 terminates in a bar 114, extending substantially parallel to the back-

ing roll axis, and having at each end a forwardly extending lug 115. The opposed inner surfaces of lugs 115, 115 are spaced apart by a distance slightly greater than the overall length of a shuttle; in other words, said inner surfaces of lugs 115 are in substantially the same vertical planes as the upright track surfaces 61, 61, so as to perform the same functions as said track surfaces in guiding a shuttle and preventing its endwise displacement in either direction. Below these movable lugs 115, the bridge 12 supports similarly-arranged stationary lugs 116, 116; these lugs 116, 116 are at such a level that after a shuttle has been lowered into the grinding throat, they slightly overlap the ends of said shuttle and thus serve to prevent its endwise displacement in either direction while the grinding operation on the contained workpiece is being performed.

Upon completion of such a grinding operation the operator by depression of a conveniently-located switch button 117 (see Fig. 5), causes pressure fluid to be admitted to the left hand end of cylinder 107, driving piston 106 to the right, and thereby rocking member 104 upwardly, as shown by broken lines in Fig. 2; this movement elevates the pressure roll 15 into inoperative position and simultaneously subjects a shuttle then in the grinding throat to an upward and outward push by bar 114; this causes the thus-freed shuttle to be lifted as shown by broken lines in Fig. 2 over the top of support roll 14 and discharged onto the tracks 60b, 60b; during this discharge any endwise shifting of the shuttle is prevented by the inner surfaces of lugs 115, 115. Subsequently, and while the pressure fluid admitted to cylinder 107 is still effective to hold the roll 15 and the arm 113 in the raised broken line position of Fig. 2, a newly-loaded shuttle is rolled along tracks 60b, 60b toward the grinding throat; at about the point of its dropping off the end of said tracks, it encounters by its surfaces 31a, 31a the then-elevated bar 114 whose lugs 115, 115 are in position at this time to overlap the ends of the shuttle and prevent its endwise displacement. Thereupon the operator depresses a second conveniently located switch button 118 (see Fig. 5) to initiate the discharge of pressure fluid from cylinder 107, for return of the parts to the positions shown by Fig. 3; according to my invention, a shuttle so positioned at the entrance to the grinding throat, is adapted to be lowered slowly and gradually into said throat, without shock, and without possibility of damage to the accurately finished surfaces 20, 20 and 30, 30, this being accomplished by regulating and restricting the rate at which the fluid under pressure is permitted to discharge from the cylinder 107, so as to materially slow down the return of arm 113 to the position shown in Fig. 3.

Fig. 5 illustrates schematically an arrangement of hydraulic devices for this purpose, in conjunction with the electrical circuits, containing the above-mentioned switch buttons 117 and 118 for actuation of said hydraulic devices. As shown in this diagram, the cylinder 107 is provided near its left hand end with two fluid pressure ports 119 and 120, the former being nearer said end, and both being connected to a conduit 121 which communicates through choke coil 122 with a fluid pressure line 123 to which fluid under pressure is supplied by a suitable pump 124. The supply line 123 has a branch 125 leading to a recess 126 in a valve bore 127 wherein is disposed a slide valve 128; from a second recess 129 of said bore there leads a conduit 130 which has

two branches 131 and 132 communicating with the conduit 121. In branch 131 is a downwardly-opening check valve 133 and in branch 132 is a pressure regulating valve 134 of well-known type. A third recess 135 in valve bore 127 is connected by an exhaust conduit 136 with a tank 137 containing the fluid, usually oil, that is put under pressure by the pump 124.

The valve 128 as shown, comprises two piston portions 138 and 139, connected by a portion 140 of reduced diameter. Said valve is arranged to be operated by a pair of solenoids 141 and 142, these adapted to be energized by the depression, respectively of the push button switches 117 and 118. To this end, said solenoids are connected as shown by Fig. 5 in electrical circuits containing said switches 117 and 118, in such manner that the depression of button 117 will complete a circuit (shown by dotted arrows) through solenoid 141, to draw valve 128 to the left, where its reduced portion 140 connects the bore recesses 126 and 129, leaving the third recess 135 covered and shut off by the piston portion 138. In this left hand position of valve 128, fluid under pressure from branch 125 is admitted by the valve to conduit 130 and flows unrestrictedly through check valve 133 to the cylinder 107, where it drives the piston 106 to the right, for the elevation of pressure roll 15 and the simultaneous discharge of a shuttle from the grinding throat, by action of bar 114 as above described.

Subsequently, after positioning of another shuttle at the entrance to the grinding throat, the push button 118 is depressed; this completes a circuit (shown by heavy line arrows) through the solenoid 142, which draws the valve 128 into its right hand position shown by Fig. 5, cutting off by piston portion 138 the supply recess 126 and connecting by reduced portion 140 the recesses 129 and 135. This, of course, deprives the fluid in cylinder 107 of the pump pressure, whereupon the piston 106, then at the right hand end of said cylinder, begins a movement to the left, under the influence of gravity acting upon the elevated member 104. The fluid at the left of said piston is driven out through ports 119 and 120, this expulsion being permitted by the fact that the valve 128 in this full line position connects the recess 129 with the recess 135, the latter exhausting to the tank 137. However, such expulsion of the fluid from cylinder 107 is not free and unrestricted, because in this direction of flow, the check valve 133 is closed, compelling the expelled fluid to pass at a reduced rate of flow through either the pressure regulating valve 134 or the choke coil 122. This retardation of flow imposed upon the fluid discharging from the cylinder 107 results in a relatively slow downward movement of member 104 and arm 113, so that the shuttle resting against the bar 114, instead of being allowed to drop into the grinding throat, is gradually and slowly lowered into said throat, thus avoiding all impact of the shuttle surfaces 30, 30 against the rolls 13 and 14.

Before the so-lowered shuttle comes to rest against the roll 13, at the bottom of the grinding throat, there is effected a further slowing-down of the lowering movement, this occurring when the port 120 is covered by the leftwardly-moving piston 106, which leaves the port 119 as the only exit for the fluid from cylinder 107. For a close control of this final extremely slow shuttle-depositing movement, said port 119 is prefer-

ably provided as shown with an adjustable needle valve 143, which can be positioned to give the desired rate of flow for this final shuttle-depositing movement. The electrical circuits shown by Fig. 5 are so arranged that depression of the push buttons 117 and 118 will be ineffective to raise and lower the member 104 unless the grinding wheel 8 on table 3 has previously been moved out of the bore of a piece of work occupying the grinding throat of the machine. To this end, the line which supplies electric current to the circuits controlled by said push buttons contains a make and break contactor 144, the latter's position being controlled by a coil 145 which is in another circuit that contains a switch 146. Said switch 146 has a movable contact member 147 whose position is controlled by a cam bar 148 carried by table 3. With said table in a position that removes the grinding wheel 8 from the grinding throat, the low part of cam bar 148 allows member 147 to rise, thus keeping said secondary circuit open, with coil 145 un-energized, so that contactor 144 remains in its full-line position, to maintain at this point the circuits containing the push buttons 117 and 118. However, with the table 3 moved to a position that carries the grinding wheel 8 into the grinding throat, the high part 149 of cam bar 148 depresses switch member 147 to close said secondary circuit, thereby energizing the coil 145 and drawing the contactor 144 into its open broken-line position; this breaks both the circuits controlled by the push buttons 117 and 118. Thus, when the grinding wheel 8 is in the grinding throat, no raising or lowering of pressure roll carrier 104 can be made to take place, by operation of push buttons 117 and 118. In this way, all chance of damage to the work or to the machine, by inadvertent actuation of the shuttle-discharging and handling devices, is effectually averted.

Fig. 2 shows in full lines a shuttle 22 in the grinding throat, for the usual bore grinding operation by grinding wheel 8 on the contained workpiece. It will be understood that for each grinding operation, the approach of the grinding wheel to grinding position, its reciprocation lengthwise of the workpiece in said grinding position and its withdrawal movements, for dressing, and at the conclusion of the grinding operation, are effected in any well-known manner, preferably by hydraulic actuation of table 3 by its connection to a piston-and-cylinder unit shown in Fig. 2 at 150. The latter is controlled and operated in a manner well known in machines of this class, by reversing member 151 which is engaged by suitable table dogs 152 and 153, the control devices also including a starting lever 154 and a speed control lever 155.

In my improved machine, the workpieces derive rotation during grinding from members which have no overhang beyond their supporting bearings, in consequence of which the axis of workpiece rotation is not subject to any deflection by grinding or other pressures. Such pressures are transmitted by the spaced end surfaces 30, 30 of the shuttle, to the backing roll surfaces 20, 20, which being immediately adjacent to and between the bearings of said roll, provide the maximum resistance to deflection.

I claim:

1. In a centerless internal grinding machine to which each workpiece is presented for bore grinding while held in a hollow shuttle having a pre-formed external surface adapted for rolling con-

tact with the rotary elements forming the grinding throat of said machine, a track on which each such shuttle is rolled to the entrance of said throat, said track having a higher level of shuttle-support than said throat and means for retarding the gravity descent of each shuttle from said track into said throat, said means being movable against a shuttle in said throat to discharge same onto said track.

2. In a centerless internal grinding machine to which each workpiece is presented for bore grinding while held in a hollow shuttle having a pre-formed external surface adapted for rolling contact with the rotary elements forming the grinding throat of said machine, a track on which each shuttle is rolled to the entrance of said throat, said track having a higher level of shuttle-support than said throat, a member movable hydraulically to discharge a shuttle from said throat, and means for controlling the reverse movement of said member to lower a shuttle from said track into said throat without appreciable impact of its said surface against said rotary elements.

3. In a centerless internal grinding machine to which each workpiece is presented for bore grinding while held in a hollow shuttle having a pre-formed external surface adapted for rolling contact with the rotary elements forming the grinding throat of said machine, a member movable in one direction to discharge a shuttle from said throat and in the other direction to lower a shuttle into said throat without appreciable impact of its said surface against said rotary elements, actuators for said member, selectively controlled by the operator, for procuring the shuttle-discharging and shuttle-lowering movements of said member, and means for preventing operation of either of said actuators by the operator until the grinding wheel of said machine has been withdrawn from said grinding throat.

4. In a centerless internal grinding machine to

which each workpiece is presented for bore grinding while held in a hollow shuttle having a pre-formed external surface adapted for rolling contact with the rotary elements forming the grinding throat of said machine, a member movable in one direction to discharge a shuttle from said throat, and in the other direction to lower a shuttle into said throat, devices selectively operable to obtain the shuttle-discharging and shuttle-lowering movements of said member, and means for rendering both of said devices inoperable by the operator when the grinding wheel of said machine is in said grinding throat.

5. In a centerless internal grinding machine, a plurality of rotary elements forming a grinding throat and with which elements the work is adapted to have rolling contact for its support and rotation during grinding, a track arranged for the rolling movement of the work to the entrance of said throat, said track having a higher level of work support than said throat, a member movable hydraulically to discharge work from said throat, and means for controlling the reverse movement of said member to lower the work from said track into said throat without appreciable impact of said work against said rotary elements.

6. In a centerless internal grinding machine, a plurality of rotary elements forming a grinding throat and with which elements the work is adapted to have rolling contact for its support and rotation during grinding, a member movable in one direction to discharge work from said throat and in the other direction to lower the work into said throat, devices selectively operable to obtain the work-discharging and work-lowering movement of said member, and means for rendering both of said devices inoperable by the operator when the grinding wheel of said machine is in said grinding throat.

RICHARD A. HEALD.
